JOSEPH A. PARRELLA,

BY

James M. Gle
ATTORNEY.

UNITED STATES PATENT OFFICE

JOSEPH A. PARRELLA, OF WASHINGTON, DISTRICT OF COLUMBIA

KEY POUCH

Application filed October 1, 1929. Serial No. 396,519.

This invention relates to an improvement in key pouches, and has for its object, means to support a plurality of sets of keys, each set independent of the other.

It is an object of the present invention to provide a key pouch so constructed as to encase and pivotally support two separate sets of keys in such manner that either set may be brought into use without disturbing the other set.

Another object is to construct such a key pouch, so formed as to provide in effect two separate key containing pockets for receiving and pivotally supporting two separate sets of keys, and to further provide closure means for each of the pockets whereby one of the pockets may be opened independent of the other pocket.

A further object of the invention is the provision of a key pouch of extremely simple design, which is strong, durable and will support a plurality of sets of keys to a high degree of efficiency.

Other important objects and advantages of the invention will be apparent from the detailed description which follows:

In the accompanying drawings:

Fig. 1 is a perspective view of a key case constructed in accordance with the invention,

Fig. 2 is a similar view with one of the pockets opened,

Fig. 3 is a vertical longitudinal section thereof,

Fig. 4 is an end view,

Fig. 5 is a view of blank for forming the pouch prior to assembly, and

Fig. 6 is a perspective view of a slightly modified form of the invention.

Referring to the drawings, in detail, the numeral 10 designates the key pouch as a whole, embodying side walls 11 and 12, and a bottom wall 13. As clearly shown, the ends of the walls 11 and 12 are preferably rounded, and each side wall is provided with apertures 14 and 15 for receiving two part pivot post members 16, of any well known design. The members 16 are adapted to support sets of keys 17 and 18, respectively, and it is preferable that each member 16

be of such size as to support three or four keys of usual design. The members 16 are of course, provided with enlarged heads 19 preventing their passage through the openings 14 and 15.

The side 11 is provided with integral flaps 20 and 21, adapted to be folded across the open side of the pouch and these flaps carry female members 22 and 23, of resilient snap fasteners, while the wall 12 carries the male members 24 and 25 of such fasteners. Thus, it will be seen that when the flaps are folded over the open side of the pouch and the snap fasteners engaged, the pouch will be effectively held closed, thereby retaining the keys 17 and 18 securely nested. As clearly shown, the member 23 may have the word "Auto" stamped on its face, the purpose of which is to indicate to the user the keys contained in that pocket. The members 22 and 23 are, preferably set back sufficiently far from the ends of the flaps to provide a lifting edge for such flaps.

As shown in Fig. 3, the flaps 20 and 21 are spaced in such manner as to provide sufficient clearance for the swinging of the keys upon their pivots, thus providing in effect, an independent pocket for each set of keys. The flaps may be of any ornamental shape or design, and the wedge shape, as shown, is preferable, although not essential. As shown in Fig. 5, the entire pouch is formed from a single piece of material folded upon itself, and is formed of leather, or other flexible material.

In Fig. 6, a slightly modified form of the invention is illustrated. This form of pouch embodies the same side and bottom wall 11, 12 and 13, rounded at their ends, and provided with the same key pivot posts 16. In this form of the invention, the flaps 20 and 21 are omitted, and in lieu thereof the sides are extended at points 26 and 27, and carry the same separable snap fasteners. This form of the invention is identical with the preferred form in operation.

In use, the operator merely notes which keys he wants to use, and having determined this, the flap covering that pocket is opened, and the keys are then either swung outward.

ly by the finger, or the case, as a whole, inverted and shaken, whereby the keys of that particular set swing outwardly upon their pivot. That key which is desired is then selected and the others swung back into the pocket and the flap resnapped. It is, therefore, obvious that the shaking of the keys from one pocket will be independent entirely of the keys of the other pocket, these being securely held in place by the independent flap of such pocket.

It will be obvious, from the foregoing, that an extremely simple and efficient key pouch has been provided. The keys are always securely held in the pockets by the flaps, and are readily removable at the will of the operator. The shape and design is such as to cause the pouch to lie snugly in the pocket of the user. Further, the keys are always held properly arranged and cannot become tangled as is the case with those cases having supporting means, such as snap hooks.

It is to be understood that the invention is not limited to the precise construction set forth, but that it includes within its purview whatever changes fairly come within either the terms or the spirit of the appended claims.

Having described my invention, what I claim is:

1. A key pouch formed of a sheet of flexible material folded upon itself for providing opposed walls, key supporting means connecting the walls adjacent their ends for pivotally supporting sets of keys and independent snap means connecting the walls at spaced points for controlling the swinging of each set of keys independently.

2. A key pouch formed of a sheet of flexible material folded upon itself, comprising opposed side walls, key posts uniting the said walls adjacent their ends and adapted to pivotally support sets of keys, flaps carried by one of said walls and adapted to fold over the other of said walls, and separable snap fasteners for uniting the free ends of said flaps with the second named wall.

3. A key pouch formed of a sheet of flexible material folded upon itself, providing opposed walls, key supporting posts connecting the walls adjacent their ends, and means carried by one of said walls for forming independent key receiving pockets.

4. A key pouch of rectangular shape formed from a sheet of flexible material, folded upon itself, for forming opposed side walls, key posts uniting the walls adjacent their ends and adapted to pivotally support independent sets of keys, spaced flaps carried by one of the walls, said flaps equidistantly spaced from the ends of the wall, and coacting separable means for connecting the free ends of said flaps with the opposite wall, said flaps acting to retain the keys

against swinging movement upon their respective posts.

5. A key pouch of rectangular shape, formed from a single sheet of flexible material, folded upon itself, for providing opposed spaced walls, united at their lower edge, key posts connecting the ends of said wall and adapted to pivotally support independent sets of keys, integral flaps carried by one of said walls and equidistantly spaced from the ends of the wall, said flaps adapted to be folded over the other of said walls for connecting said walls at their upper edges, snap fasteners for detachably connecting said flaps with the last named wall, said flaps so spaced with respect to each other as to permit the outward swinging movement of one set of keys independent of the other.

6. A key pouch comprising a pair of opposed walls permanently united at one edge, posts carried by the opposite ends of said pouch for pivotally supporting sets of keys and separable means for uniting the free edges of the pouch at two different points for retaining the sets of keys independently.

In testimony whereof I affix my signature.

JOSEPH A. PARRELLA.
